United States Patent Office

Des. 217,741
Patented June 2, 1970

217,741

OVERHEAD PROJECTOR

Robert M. Simonelli, Palatine, Ill., assignor to GAF Corporation, New York, N.Y., a corporation of Delaware

Filed May 26, 1969, Ser. No. 17,343

Term of patent 14 years

Int. Cl. D16—03

U.S. Cl. D61—1

FIG. 3

FIG. 2

FIG. 1 is a perspective view of an overhead projector embodying my new design;

FIG. 2 is a reduced front elevational view thereof;

FIG. 3 is a rear elevational view thereof;

FIG. 4 is a left-side elevational view thereof, the right side (not shown) being substantially a mirror image of the side shown; and

FIG. 5 is a top plan view thereof.

The bottom of the overhead projector is plain and unornamented.

I claim:

The ornamental design for an overhead projector, substantially as shown and described.
